CLAIM

The ornamental design for a display panel or screen with graphical user interface, as shown and described.

DESCRIPTION

FIG. 1 is a front view of a display panel or screen with graphical user interface showing a first embodiment of my new design;

FIG. 2 is a front view of a second embodiment thereof;

FIG. 3 is a front view of a third embodiment thereof;

FIG. 4 is a front view of a fourth embodiment thereof; and,

FIG. 5 is a front view of a fifth embodiment thereof.

The broken lines in the drawings illustrate the display screen and portions of the graphical user interface and form no part of the claimed design.
